UNITED STATES PATENT OFFICE.

ARTHUR F. PINE, OF CASTLE ROCK, COLORADO.

VEHICLE-SPRING.

1,262,252.

Specification of Letters Patent.

Patented Apr. 9, 1918.

Application filed September 29, 1916. Serial No. 122,787.

To all whom it may concern:

Be it known that I, ARTHUR F. PINE, citizen of the United States, residing at Castle Rock, county of Douglas, and State of Colorado, have invented new and useful Improvements in Vehicle-Springs, of which the following is a specification.

My invention relates to improvements in vehicle springs of that type which are commonly designated as leaf springs.

The objects of my invention are to provide a form of construction in which some leaves of a spring composed of a series of flat superposed and contacting leaves, will act in opposition to the others within a limited range or field of movement, while beyond such field of movement all the leaves will coöperate with each other. Also to provide improved means to impart rigidity to the central portion of the spring. A further object of my invention is to provide a suitable device for connecting the outer ends of oppositely flexing spring leaves with each other, whereby separation of the leaves at their respective ends may be prevented.

In the drawings—

Figure 1 is a side elevation of a vehicle spring embodying my invention.

Fig. 2 is a plan view of same.

Fig. 3 is a detail view in longitudinal section showing a fragment of a set of leaves embodying my invention as they appear under normal flexion prior to the operation of clamping them to the vehicle axle or to each other.

Fig. 4 is a cross sectional view drawn to a plane on line 4—4 of Fig. 1, but showing a modified form of clamp.

Fig. 5 is a cross sectional view drawn to a plane on line 5—5 of Fig. 1, and showing a modified form of intermediate retaining clip.

Fig. 6 is a perspective view of one of the central clamping plates, preferably employed.

Fig. 7 is a detail view of one of the anti-rattling coils for the intermediate clip shown in Fig. 5.

Fig. 8 is a cross sectional view drawn on line 8—8 of Fig. 1, but showing all the leaves corrugated in the same direction.

Like parts are identified by the same reference characters throughout the several views.

My improved spring includes a main leaf 1, the extremities of which are provided

with eyes 2 to facilitate connecting the spring with a vehicle frame. This spring is reinforced by a set of auxiliary leaves 3, 4, 5 and 6 of progressively decreasing length. 60 The general function of these leaves and the coöperative relation to the main spring 1, is substantially the same as in all ordinary vehicle springs of the leaf type in common use, but in addition to these leaves, I mount 65 a second auxiliary set of leaves 7, 8 and 9 respectively, on the opposite side of the main leaf. Each of these auxiliary leaves of the second set, is formed to exert tension against the main leaf 1 in the opposite direction 70 from that exerted by the auxiliary leaves 3, 4, 5 and 6 under normal conditions. The leaves 7, 8 and 9 are also of progressively decreased length, the leaf 7 being the longest and the leaf 9 the shortest. In assembling the leaves to form the spring, they will when superposed, assume substantially the positions in which they are illustrated in Fig. 3, with their central portions separated and their end portions in contact. The normal curvature of leaves 3, 4, 5 and 6 is greater than that of the main leaf and the normal curvature of the leaves 7, 8 and 9 is less than that of the main leaf 1. Therefore, when clamped together at the center as 75 shown in Fig. 1, the end portions of the leaves 3, 4, 5 and 6 will exert upward pressure against the main leaf 1, whereas end portions of leaves 7, 8 and 9 will exert a downward pressure thereon. This condition will continue during the flexion of the spring in either direction from the normal position until one or the other auxiliary set 80 is moved, not only to, but past its normal curve which the leaves composing such set 90 assume before assembly in binding relation to each other, but whenever the flexion of the spring becomes so great in the direction in which any leaf exerts normal tension as to carry the spring past its line of normal 100 curvature, then such leaf becomes coöperative with the auxiliary leaves of the other side in opposing further flexion. For example, if it be assumed that a load placed on the ends of the spring shown in Fig. 1, 105 tends to straighten the spring from its normal bow form, it is obvious that the initial flexion will be aided by the downward pressure exerted by the ends of the auxiliary leaves 7, 8 and 9 and will be opposed by the 110 auxiliary leaves of the lower set 3, 4, 5 and 6. If the flexion continues until the normal

curve lines of the leaves 7, 8 and 9 have been crossed; said leaves 7, 8 and 9 will then coöperate with the main leaf and with the auxiliary leaves in opposing such continued flexion.

Assuming that the load is suddenly removed, the recoil of the spring will cause the outer portions of the springs to move upwardly and as soon as the normal curve lines of the upper set of auxiliary leaves 7, 8 and 9 have been crossed, said leaves will exert a progressively increasing downward pressure upon the main leaf 1, thereby resisting the recoil before the lower set of coöperative leaves 3 to 6 inclusive have reached their normal curve lines. The upper set of auxiliary leaves are, therefore, adapted to prevent a too violent recoil and they are also adapted to modify the recoil movement in such a manner as to gradually limit it and reduce the field of movement without shock. The lower set of auxiliary leaves will, of course, act in a somewhat similar manner, first, in opposition to and then in coöperation with the leaves 7, 8 and 9 of the upper set, in case a sudden load shock is imparted to the spring in any direction which tends to straighten it. The ends of the auxiliary leaves are connected together by clips comprising cross plates 13 and 14 and clamping bolts 15. These clips may be of ordinary construction, or if desired, the upper cross piece may compose a bolt 17 provided with rollers 18 adapted to bear upon the top leaf, together with wire springs 20 coiled about the bolts with end portions bearing upon the top leaf substantially as shown. These rollers and coiled wire springs are, however, not essential to my invention.

The leaves composing the middle portion of the spring are clamped together by a set of stirrup-shaped clips 22 which may be of ordinary construction as shown in Fig. 1, in which case these clips have threaded extremities extended through a clamping plate 23 adapted to engage underneath a vehicle axle 24, the extremities of the clips receiving the clamping nuts 25 and a supporting plate 26 being interposed between the axle and the central portion of the spring. If desired however, clamping plates 29 and 30, of special form, may be employed as illustrated in Figs. 4 and 6, these clamping plates being adjusted across the central portion of the spring as illustrated and connected by clamping bolts 21.

The central portion of the main leaf 1 and also the central portions of each of the auxiliary leaves 3, 4, 5 and 6, respectively, are longitudinally corrugated at their central axes. These corrugations all bulge in the same direction (downwardly in Figs. 1 and 3) and are arranged to interfit, the corrugations in leaf 1 projecting into the hollow

or concavity formed by the corrugation in leaf 3, etc. Leaves 7, 8 and 9 are similarly corrugated but in the opposite direction (i. e., upwardly in Figs. 1 and 3). The concave cavity thus formed in the under surface of leaf 7 registers with the similar cavity in the upper surface of leaf 1, thereby forming a chamber having a generally oval form which I preferably fill with an anchor or core piece 35. The interfitting corrugations and also the anchor piece not only strengthen the central portion of the spring and impart rigidity thereto but also prevent the leaves of the spring from sliding longitudinally upon each other. Further, they coöperate with the intermediate clips in preventing lateral swinging movements of the leaves. The upper and lower clamping plates, if used in connection with the clips 22, will, of course, have their spring engaging faces contoured to fit the corrugated portions of the spring leaves which the plates directly engage. For example, the cavity 37, illustrated in the supporting plates shown in Fig. 6, is adapted to receive the corrugations formed in the leaf 6.

I do not limit the scope of my invention to any specific number of auxiliary leaves, the essential feature of my invention residing in the fact that one or more auxiliary leaves are employed on opposite sides of the main leaf and are normally curved so that each will exert tension upon the main leaf in a direction opposite to the tension of the auxiliary leaf or leaves located on the opposite side of the main leaf. It will also be understood that while I have referred to the main leaf as comprising a single leaf, it is not essential that this leaf should be a single leaf as distinguished from a plurality of leaves. Further, while I have shown my vehicle spring as a semi-elliptical spring, having its central portion connected with a vehicle axle, it is not essential that my improved spring should be so used or assembled with its end portions connected to the vehicle frame and its central portions to the axle. On the contrary, the improved spring may be employed in any relation where a bowed spring may be used. The corrugations and also the intermediate clips may be omitted, if desired, or modified to any extent without departing from the scope of my invention.

I claim—

1. A vehicle spring comprising a main leaf, and auxiliary leaves on opposite sides of the main leaf, each arranged to normally exert substantially continuous pressure in the direction of the main leaf throughout its length, said main leaf and the auxiliary leaves on one side of the main leaf having their central portions provided with longitudinally extending interfitting corrugations.

2. A vehicle spring comprising a main leaf, and auxiliary leaves on opposite sides of the main leaf, each arranged to normally exert substantially continuous pressure in the direction of the main leaf throughout its length, said main leaf and the auxiliary leaves on one side of the main leaf having their central portions provided with longitudinally extending interfitting corrugations, and the auxiliary leaves on the other side of the main leaf being provided with longitudinal corrugations bulged in an opposite direction. 10
3. A vehicle spring comprising a plurality of leaves, arranged in two sets, the leaves of one set being provided adjacent their centers with interfitting corrugations lying entirely within the contour of the leaves and bulged in one direction, and the leaves of the other set being provided adjacent their centers with interfitting corrugations lying entirely within the contour of the leaves and bulged in an opposite direction, the leaves of the respective sets being in continuous contact along their longitudinal edges. 15
4. A vehicle spring comprising two sets of leaves, the leaves of one set being provided adjacent their central portions with interfitting corrugations which lie entirely within the contour of the leaves and are bulged in an opposite direction, the corrugations of the innermost leaves of the two sets defining a peripherally continuous compartment; and a filler removably seated in the compartment to prevent relative movement between the two sets of leaves. 20
5. A vehicle spring comprising spaced leaves; links assembled with one leaf; a shaft connecting the links; spaced rollers journaled upon the shaft and engaging another leaf; and a supplemental spring engaged in its intermediate portion by the shaft and held against movement longitudinally of the shaft by the rollers, the supplemental spring 40 coacting with said other leaf. 45
6. A vehicle spring comprising leaves having oppositely bulged longitudinal recesses forming a compartment; and a filler disposed within the compartment and engaged with both springs to prevent relative movement therebetween. 50
7. A vehicle spring comprising leaves having oppositely bulged recesses located entirely within the contour of the leaves and defining a compartment located entirely within the leaves; and a removable one-piece filler disposed within the compartment and coacting with the leaves to prevent relative movement therebetween, the filler being 55 wholly inclosed by the leaves. 60
8. A vehicle spring comprising a series of leaves having their central portions longitudinally recessed on one side and provided with a corresponding bulge on the other side, the bulged portion of each leaf except the last in the series fitting into the recess of the juxtaposed leaf. 65

In testimony whereof I affix my signature in the presence of two witnesses.

ARTHUR F. PINE.
